FUEL PUMPING DEVICE

Filed April 14, 1928

UNITED STATES PATENT OFFICE

WILLIAM H. SCHULZE, OF CHICAGO, ILLINOIS, ASSIGNOR TO STEWART-WARNER CORPORATION, OF CHICAGO, ILLINOIS, A CORPORATION OF VIRGINIA

FUEL PUMPING DEVICE

Application filed April 14, 1928. Serial No. 269,947.

The purpose of this invention is to provide an improved construction of a pumping device for supplying fuel to the carburetor of an internal combustion engine from a source 5 of fuel at a lower level in the carburetor, such pumping device to be actuated by connection with the moving part of the engine. It consists in the elements and features of construction shown and described as indicated 10 in the claims.

In the drawing:

Figure 1 is a diagrammatic view for the purpose of showing a pumping device embodying the invention in its relation to the 15 engine and to the fuel source of a motor vehicle.

Figure 2 is an axial section of the pumping device.

Figure 3 is a detail section of a portion of 20 the structure seen in Figure 2 showing a detail modification in respect to the cam-engaging terminal of the pumping device.

In the drawing the engine is indicated at A, the fuel source at B, and the pumping device in its entirety in Figure 1 by C. Referring to Figure 2, 20 is a cam on a rotating shaft of the engine which is utilized for actuating the pumping device. The pumping device as shown comprises two casing members, 21 and 22, formed with mated cavity-encompassing faces at which they are mounted one upon the other for clamping between them a flexible diaphragm, 23, which partitions from the cavity 24, in the face of the 25 casing member, 21, a chamber formed by a cavity, 25, in the face of the casing member, 22, said chamber, 25, constituting the pumping chamber of which the diaphragm, 23, forms a movable wall by whose movement 30 the cavity of the chamber is enlarged and reduced. To the diaphragm, 23, at the center thereof, there is attached a stem member, 30, having a reduced and threaded nipple, 31, forming a shoulder, 32; and a nut, 34, is 35 screwed onto the threaded nipple and serves for clamping the diaphragm to the stem member, 30, and for clamping the central area of the diaphragm between two sheet metal disks, 35, 35, limiting the flexibility of 40 the diaphragm to the annular portion out-

side said central area and between the latter and the marginal portion of the diaphragm which is clamped, as described, between the mated faces of the casing members, 21 and 22.

The pumping chamber has passages communicating in any convenient manner with the fuel source and with the carburetor, as the pipe, 26, leading from the fuel source, and the pipe, 27, leading to the carburetor; and said passages are controlled by check valves indicated respectively at 28 and 29, opening respectively for flow into and out of the pumping chamber, and thereby from the fuel source toward the carburetor, and seating against reverse flow; and it will be understood that the alternate movement of the diaphragm in opposite directions, first for enlarging, and then for reducing the pumping chamber capacity, serves in the chamber-enlarging stroke for producing partial vacuum in the pumping chamber, causing the fuel to be lifted to that chamber from the lower fuel source, while the opposite movement of the diaphragm for reducing the pumping chamber forces the fuel from the pumping chamber toward the carburetor.

In a pumping apparatus for advancing fuel from a fuel source toward the engine, it is of importance to avoid reversing the fuel movement so as to cause it to move alternately in the opposite direction through the same space in the operation of the pumping device, because such reversal operates for turbulence, or with "churning" effect upon the fuel, tending to interfere with the uniformity of quantity of liquid fuel fed by a given stroke of the pumping member; and to avoid such reversal, in the construction shown it will be noticed that the pumping chamber and its inflow and outflow passages and valves are relatively arranged for movement of the fuel in a continuous substantially vertical direction from the inflow valve into the pumping chamber at the lower side thereof and through the pumping chamber and out at the upper side to the outflow valve, avoiding moving it out of the chamber through the same port through which it came in.

For actuating the diaphragm alternately in the opposite directions described it is provided with a two-membered stem comprising the member, 30, above mentioned, which is attached to the diaphragm as described, and 5 a second member, 40, comprising a cam-engaging terminal and wear piece, 41, which protrudes from the body of the casing member, 21, through a stem, 21^a, with which the 10 casing member is provided for the purpose of intruding into the engine casing, and a coil spring, 42, encompassing the stem member, 40, within the casing reacts at one end against the casing member through the medium of a bushing, 21^b, which affords slide bearing for the cam-engaging terminal and wear piece, 41, of the stem member, 40, said spring reacting at the opposite end against a shoulder, 40^b, formed by reducing the said 15 stem member, 40, to form an annular chamber to accommodate said spring, 42. The terminal and wear piece, 41, of the stem member, 40, has a terminal hook, 41^a, for spanning the operating cam, 20, and shown as 20 actuated by the eccentric protuberance of the cam encountering the inner side of the hook terminal, and thereby operating to draw the stem outwardly from the casing terminal member, 21^a. The end of the stem member, 25 40, into which the terminal and wear piece, 41, is screwed, is bored to a depth considerably more than that occupied by the threaded engagement of said terminal and wear piece, and before said terminal and wear piece 30 is screwed into place, the stem member, 30, having a head, 30^a, inserted through the axial bore of the member, 40, said head, 30^a, being stopped at the bottom of the bore into which the terminal and wear piece, 41, is screwed. 35 The opposite end of the stem member, 40, is counterbored to form a shoulder, 40^x, constituting a stop for the end of a coil spring, 45, which is coiled around the stem, 30, reacting at the opposite end upon the diaphragm, 23, for stressing the diaphragm in the direction for reducing the capacity of the pumping 40 chamber.

Upon considering this construction it will be noted that the action of the cam, 20, upon 45 the stem member which is positively actuated by it, is in the direction of the pumping-chamber-enlarging movement; and that the positively actuated stem member, 40, is telescoped outside the diaphragm-connected stem member, 30. And it will be noted that 50 the spring, 45, which reacts upon the diaphragm, reacts in the direction for reducing the pumping chamber, that is, in the direction for feeding fuel to the carbureter, and 55 reacts for holding the diaphragm at the limit of its stroke in that direction by the force stored in the spring by compression to which it is subjected in the assembling of the parts. 60 And at rest position of the parts, the spring 65 reacts for holding the diaphragm at the lim-

it of its stroke in fuel feeding direction, by the force stored in said spring by the compression to which it is subjected in the original assembling of the parts. And in active operation this spring may be said to react 70 for transmitting to the diaphragm the thrust of the stem member, 41, due to the reaction of the spring, 42; but it will be observed that in this transmission the spring, 45, operates by virtue of its stiffness, and as if it were non-resilient; and that the increased reaction 75 which it may derive from the compression to which it is subjected in the feeding stroke when the fuel discharge movement is stopped by the filling of the fuel line to the carbureter and the carbureter construction for preventing over supply discharge to the engine, does not serve for fuel discharge, except as engine 80 consumption during the remainder of the stroke after the compression and yielding begins corresponds to fuel delivery. And the reaction of the spring, 42, for thrusting the stem member, 40, in the direction of the feeding stroke operates for giving the pumping member its feeding stroke only so far as the 85 spring, 45, transmits the thrust unyieldingly; or, as it might be otherwise stated, only in the sense that thrust movement of the stem member, 40, operates to release the stem member, 30, from being held by the flange, 40^x, of the stem member, 40, against the reaction of the spring 45, between the diaphragm and said flange, 40^x, tending to thrust the diaphragm in fuel feeding direction.

Accordingly at the limit of any feeding 90 movement which is actually transmitted to the fuel in the usual installation, the force by which the fuel is fed to the carbureter is substantially predetermined by the conditioning for reaction of the spring, 45, effected in the 95 original assemblage of the pump structure, and is therefore at all times substantially independent of any variations in the action of the engine or any other source of positive 100 actuation of the pumping device. In view 105 of the variation in respect to fuel lift in the case of an engine on a motor vehicle travelling the highway, due to varying grade on which the vehicle travels, it will be recognized 110 that the springs, 42 and 45 will be conditioned for reaction with adequate force for feeding the maximum fuel lift on the maximum grade, the spring, 45, being stiff enough 115 to transmit the necessary pressure for the maximum lift, and the spring, 42, being 120 enough stronger than the spring 45, to compress the latter in following the cam in the idle phase of the cam cycle to the varying degree necessary, when at the instant of or in the course of the feeding stroke the fuel line 125 to the engine is full, and no fuel movement can be caused by the feeding stroke of the diaphragm. And upon revolution it will be noticed that since the degree of pressure 130 which can be transmitted to the diaphragm,

will be limited to the stiffness of the spring, 45, according to the conditioning of that spring in the original assembling of the pump, any danger of overstraining the fuel 5 delivery line or the connections of that line to the carburetor by excessive strength of the spring, 42, is avoided by properly limiting the stiffness of the spring, 45.

In Figure 3 there is shown a slight modification in respect to the form of the positively actuated stem member, said modification consisting in making said stem member in one piece except as to the cam-engaging hook terminal, said one piece, 141, extending 15 entirely through the casing terminal, 121^a, and axially bored to the end for accommodating the telescoping head, 130^b, of the member, 130, the cam-engaging hook being applied outside the casing, the end of the stem, 20 141^x, being reduced and threaded, as seen at 141, and the hook member, 141^a, having a threaded aperture, seen at 147, for screwing it into the threaded end of the stem where it is secured in position by a jam nut, 25 148.

In this form the bushing, 121^b, corresponding to the bushing, 21^b, of Figure 2, is formed with an interior projecting key rib, 121^c, which engages a key way, 141^c, cut in 30 the side of the stem member, 141, for ensuring against any turning of the stem member, 141, in its slide bearing, which would displace the cam engaging part, 141^a, with respect to the cam, 120.

35 This function is performed in the construction of Figure 2 by providing the cam, 20, with a peripheral groove, 20^a, forming a key way and furnishing the member, 41^a, with a key projection, 41^b, engaging the key 40 way.

I claim:—

1. A fuel feeding device comprising a housing containing a pumping chamber and passages connected for inflow from a fuel 45 source and outflow toward the carburetor of the engine served, with one-way seating valves in said passages opening for flow toward the carburetor and seating against reverse flow, the pumping chamber having a 50 movable wall member by whose opposite movements the chamber capacity is enlarged and reduced; means for moving said pumping chamber wall in said opposite directions consisting of a two-membered stem of which one 55 member is secured to the movable wall member and the other is exposed to positive actuation in the direction of the chamber-enlarging movement of the movable wall member by means exterior to the casing; a spring reacting between the casing and the last mentioned stem member to retract the latter in the direction of the chamber-reducing movement of said wall member; the two stem members being longitudinally movable relative to each 60 other for extending and reducing the stem, 65

and having co-operating stops limiting such extension and at said limit engaged with each other by said stops for longitudinal movement of the first mentioned stem member in the chamber-enlarging direction, and a second spring weaker than the first reacting on the first mentioned stem member and said movable wall member for transmitting movement of said second mentioned stem member to said wall member in chamber-reducing direction. 70

2. A liquid pumping device comprising a housing containing a pumping chamber with inflow and outflow passages and valves controlling one-way flow of the liquid pumped, 80 the pumping chamber having a movable wall member by whose movement in opposite directions the chamber capacity is enlarged and reduced; means for moving said movable wall member in said opposite directions consisting of a two-membered stem of which the first member is secured to the movable wall member for positively moving therewith and the second is exposed to positive actuation in the direction of the chamber-enlarging movement of said movable wall member; a spring reacting between the casing and the second stem member to retract said second stem member in the direction of the chamber-reducing movement of said movable wall member, the two stem members being movable relatively to each other for extending and reducing the operative length of the total stem and having cooperating stops 90 limiting said extension and adapted at said limit to be engaged with each other by said stops for effecting longitudinal movement of said first stem member in chamber-enlarging direction, and a second spring reacting at one end on the second stem member and at 100 the opposite end on the movable wall member, and thereby on the first stem member for holding the stops separably engaged with each other. 95

3. A fuel pump for internal combustion engines comprising a pump casing, a movable pumping member supported by said casing and cooperating with a pumping chamber within said casing for intake and discharge of fuel, a reciprocable operating member having a constant stroke and connected with said pumping member with provision for lost motion, means for positively moving said operating member in one direction for transmitting a positive suction stroke to said pumping member, said lost motion connection acting positively when the operating member moves to give the pumping member its suction stroke, resilient means for returning said member, and additional resilient means interposed between said member and said pumping member for limiting the discharge impulse and permitting a variable discharge stroke. 110

4. A fuel pump for internal combustion 130

engines comprising a pump casing adapted to be mounted on an engine casing adjacent an aperture thereof, a reciprocable pumping member within said casing adapted to co-operate with a pumping chamber therein, an operating stem secured to said pumping member, a second operating stem associated with said first stem with provision for lost motion, said stems having cooperating stops for limiting relative movement in one direction, engine-driven means for positively moving said second stem in a direction to transmit a positive suction stroke to said pumping member through said first stem, resilient means reacting between said stems to normally hold said stems in stopped relation for movement as a unit, additional resilient means reacting upon said second stem to transmit a discharge movement to said pumping member and said first stem by acting through said first mentioned resilient means, said additional resilient means having an effective force capable of overcoming said first-mentioned resilient means and adapted to be conditioned for reaction by the positive suction stroke of said pumping member.

5. A pumping apparatus for supplying fuel comprising a reciprocable pumping member, a stem secured to said pumping member, a sleeve slidable relative to said stem, cooperating abutments on said stem and sleeve for limiting movement in one direction; means for actuating the sleeve in one direction to transmit the positive suction stroke to said pumping member through said stem and abutment, resilient means reacting between said stem and sleeve to hold said abutment in engagement and preventing relative movement, and additional resilient means for producing movement of said sleeve in a discharge direction and having an effective force capable of overcoming said first named resilient means, whereby the movement of said sleeve is yieldingly transmitted through said first named resilient means to said pumping member for permitting a variable discharge stroke.

In testimony whereof, I have hereunto set my hand at Chicago, Illinois, this 31 day of 50 March, 1928.

WILLIAM H. SCHULZE.
